FIG. 2

INVENTOR

JOHN F. RUDE

By Toulmin & Toulmin
ATTORNEYS

UNITED STATES PATENT OFFICE

134,347

DESIGN FOR A ROTARY HOE SURFACE CULTIVATOR

John F. Rude, Evansville, Ind., assignor to Blount Plow Works, Evansville, Ind., a corporation of Indiana

Application February 2, 1942, Serial No. 105,571

Term of patent 14 years

To all whom it may concern:

Be it known that I, John F. Rude, a citizen of the United States, residing at Evansville, in the county of Vanderburgh and State of Indiana, have invented a new, original, and ornamental Design for a Rotary Hoe Surface Cultivator, of which the following is a specification, reference being had to the accompanying drawing, forming a part thereof wherein:

Figure 1 is a top perspective view of a rotary hoe surface cultivator, showing my new design; and

Figure 2 is a bottom perspective view thereof.

I claim:

The ornamental design for a rotary hoe surface cultivator, substantially as shown.

JOHN F. RUDE.
